UNITED STATES PATENT OFFICE.

JOHN ARTHUR KEESEY, OF BROOKLYN, NEW YORK, AND ALFRED SHEDLOCK, OF CANNONDALE, CONNECTICUT; SAID SHEDLOCK ASSIGNOR TO SAID KEESEY.

SIGNALING APPARATUS.

1,310,623.

Specification of Letters Patent. Patented July 22, 1919.

Application filed September 12, 1918. Serial No. 253,701.

To all whom it may concern:

Be it known that we, JOHN ARTHUR KEESEY and ALFRED SHEDLOCK, citizens of the United States, residing, respectively, at 5 Brooklyn, county of Kings, State of New York, and Cannondale, Fairfield county, State of Connecticut, have jointly invented new and useful Improvements in Signaling Apparatus, of which the following is a specification.

The salient feature of this invention is providing a conical surface for the message indications of a signaling apparatus, whereby said messages may be more readily observed by the operator, while standing naturally, than when such markings are on cylindrical or flat surfaces. This point of advantage is particularly enhanced in multi-message sending and receiving apparatus. 15 In such cases the conical message indicator will preferably be arranged on a common axis in different vertical planes, each having its message sending devices and operating handle and its return message device with 20 suitable index also operative on the common axis. The conical indicators may constitute the top of the frame or casing of the apparatus, and in multi-signaling apparatus the conical shells will preferably increase in size from the front to the rear of 25 the apparatus.

It is also contemplated to utilize the conical shells as the gongs of sound producing mechanisms, as, with other details of construction, will now be described by reference had to the accompanying drawings; in which:

Figure 1 is a plan view of an apparatus embodying our invention.

40 Fig. 2 is a front elevation.

Fig. 3 is a longitudinal vertical section, and

Fig. 4 is a transverse section on line 4, 4, 45 Fig. 3.

The casing in which the working parts are inclosed comprises a frame 5, substantially rectangular, having side flanges 6, from which vertically extend irregular shaped flanges 7, and semicircular front and back plates 8 and 9. These plates 8 and 9 are, 50 to facilitate the molding operations preferably cast separately and secured by screws or rivets to the front and back walls of the part 5, respectively. The top of the casing 55 consists of semi-circular conical plates or

shells 10, 11 and 12, on which the messages or orders are painted or otherwise indicated, here shown as communications between the officers' and engineers' stations. The conical shells are secured to the flanges 7, by 60 screws 13. There are gaps or spaces between the adjacent circular edges of these plates, between the front edge of the foremost plate 10 and the front of the frame and between the back edge of the rear plate 12 and the 65 back of the frame. The operating handles 14, 15 and 16, provided with pointers 17, 18 and 19 respectively, and the return message indices or arrows 20, 21 and 22 extend through said gap.

70 The apparatus shown comprises three distinct message sending and receiving devices each adapted, through suitable transmitting connections to operate and be operated by an apparatus located at separate stations or at 75 separate engines or machines. The advantage of the conical message indicator is that the markings thereon are practically all in one line of vision of the operator while standing in a natural position, whether there 80 be one, three, as shown, or more. When a plurality of message sending and receiving devices are included in a single apparatus it is preferred to increase the diameters of the 85 conical message indicators from the front to the rear of the apparatus, thus bringing their surfaces into approximately one plane of vision at a suitable angle for observation. Centrally supported in the front and back 90 walls of the frame 5 is a bearing rod or shaft 23, on which rotate chain wheels or pulleys 24, located beneath the conical plates or shells 10, 11 and 12, and on the sleeve of each of these pulleys is a pulley or wheel 25, adapted to be actuated from a distant station. A chain 26 is carried by each of the 95 pulleys 24 and 25.

The operating handles 14, 15, 16 are rigidly attached to the pulleys 24, under the conical shells 10, 11 and 12 respectively, and 100 similarly the indices or arrows 20, 21, 22 are attached to the return signal or message pulleys 25.

105 In some cases the return signal devices may be omitted. Aural signals are sometimes required when return messages are indicated on the main station signaling apparatus. To meet this requirement we have devised a simple double acting striking mechanism, as follows, utilizing the conical 110

shells of the casing as the sound giving parts thereof. Between each pair of chain pulleys 24, 25, is a bracket 27, secured at its base by screws, to a side wall and flange 6, 5 of the frame. Each bracket carries a plate 28, which is held thereon by headed stud bolts 29, embraced by curved slots 30, each having its center at the axis of the stud bolt of the other one. Centrally pressing against 10 the lower edge of the plate 28 is a spring 31, whose bottom end is supported on a lug 32, forming part of the bracket 27. A projection or tooth 33 laterally extends from the upper part of the face of plate 28, so located 15 as to be in the path of action of a series of circularly arranged teeth 34 projecting from the side of a return signal pulley 25, adjacent to the double rocking plate 28. A spring supported hammer 35 extends upwardly from the plate 28 and is so located normally as to be a short distance from the 20 conical message indicating shell above the striking mechanism. The hammer spring is shown as a spiral spring 36, acting as a stem 25 between the hammer and plate 28, of right resiliency to permit the hammer to rebound against the bell, that is the conical shell, when the lower end of either of the slots 30 suddenly contacts with its stud 29, by the 30 energy of the spring 31, after the plate 28 has been rocked in either direction by and suddenly released from any and all of the 35 teeth 34 of a pulley 25. An aural signal is thus given as each of the arrows 20, 21 or 22 is moved to the right or left of the zero, or normal, resting mark of the message 40 indications, said teeth 34 being spaced to cause the plate 28 to be rocked at least once as an arrow moves from message indication to another. As the resonances of the different sized conical shells, 10, 11, 12, varies a distinctive sound will be produced as the apparatus at each of the substations is manipulated.

45 We claim:

1. A signaling apparatus, comprising a casing consisting of a substantially rectangular frame having upper side flanges and a conical message indicator attached to 50 the flanges of the frame with its axis horizontally arranged, a shaft co-axial with the conical message indicator and a message sending device on the shaft including an operating handle and pointer arranged adjacent a circular edge of the conical indicator.

2. A signaling apparatus, comprising an operating handle and means connected thereto provided with a transmitting connection, a casing consisting of a substantially rectangular frame having side flanges, a conical message indicator attached by its radial edges to the flanges of the frame and constituting the top of the casing, said handle 60 rocking on a center co-axial with the conical

message indicator and adjacent to one of its circular edges, and a return message device also operative coaxially with the conical message indicator, and provided with an index adapted to move adjacent the other 70 circular edge of the conical message indicator.

3. A signaling apparatus, comprising a plurality of conical message indicators having a common axis and arranged in different 75 vertical planes with gaps between their adjacent circular edges, a message sending device for each of the conical message indicators provided with an operating handle extending through a gap, a casing, and a 80 shaft held in the casing coaxial with the conical message indicators on which the message sending devices rock.

4. A signaling apparatus, comprising a 85 plurality of conical message indicators having a common axis and arranged in different vertical planes with gaps between their adjacent circular edges, and increasing in size from the front to the rear of the apparatus, a message sending device for each of the 90 conical message indicators provided with an operating handle extending through a gap, a casing, and a shaft held in the casing coaxial with the conical message indicators on which the message sending devices rock. 95

5. A signaling apparatus, comprising a plurality of conical message indicators having a common axis and arranged in different vertical planes with gaps between their adjacent circular edges, a message sending 100 device for each of the conical message indicators provided with an operating handle extending through a gap, a casing, a shaft held in the casing coaxial with the conical message indicators on which the message 105 sending devices rock, and a return message device provided with an index for each of the conical message indicators.

6. A signaling apparatus, comprising a 110 plurality of conical message indicators having a common axis and arranged in different vertical planes with gaps between their adjacent circular edges, a message sending device for each of the conical message indicators provided with an operating handle 115 extending through a gap, adjacent the large circular edge of its conical message indicator, a casing, a shaft held in the casing coaxial with the conical message indicators on which the message sending devices rock and 120 a return message device provided with an index for each of the conical message indicators, said indices being adjacent the small circular edges of the conical message indicators.

7. A signaling apparatus, comprising a 125 casing, conical shells constituting the top of the casing, a message sending device, a return message device and a striking mechanism located beneath each conical shell,

which acts as a gong for the striking hammer of the mechanism beneath it and means for actuating the hammers by action of the return message devices.

- 5 8. A signaling apparatus, comprising a casing, conical shells arranged in different vertical planes, increasing in size from the front to the rear of the apparatus and constituting the top of the casing, a message sending device, a return message device and a striking mechanism located beneath each

conical shell, which acts as a gong for the striking hammer of the mechanism beneath it and means for actuating the hammers by action of the return message devices. 15

Signed at New York, county and State of New York, this 6th day of September, 1918.
